(57) **CLAIM**

I claim the ornamental design for a faux distributor cable holder, as shown and described.

DESCRIPTION

FIG. 1 is a perspective view of a faux distributor cable holder showing my new design;

FIG. 2 is a front elevation view of the faux distributor cable holder shown in FIG. 1;

FIG. 3 is a back elevation view of the faux distributor cable holder shown in FIG. 1;

FIG. 4 is a right elevation view of the faux distributor cable holder shown in FIG. 1;

FIG. 5 is a left elevation view of the faux distributor cable holder shown in FIG. 1;

FIG. 6 is a top plan view of the faux distributor cable holder shown in FIG. 1; and,

FIG. 7 is a bottom plan view of the faux distributor cable holder shown in FIG. 1.

The broken lines shown in the drawings are for the purpose of illustrating portions of the article and form no part of the claimed design.
